UNITED STATES PATENT OFFICE.

ALBERT L. JOHNSON, OF ST. LOUIS, MISSOURI.

CONCRETE-AND-METAL CONSTRUCTION.

No. 844,599.

Specification of Letters Patent.

Patented Feb. 19, 1907.

Application filed June 13, 1904. Serial No. 212,296.

To all whom it may concern:

Be it known that I, ALBERT L. JOHNSON, a citizen of the United States, and a resident of the city of St. Louis, and State of Missouri, 5 have invented a new and useful Improvement in Concrete-and-Metal Construction, of which the following is a specification.

My invention relates to constructions of concrete reinforced with metal, and has for 10 its principal objects to adapt such constructions for use for retaining-walls, dams, and the like.

My invention consists in the arrangements and combinations of parts, substantially as 15 hereinafter described and claimed.

In the accompanying drawings, which form part of this specification, and wherein like symbols refer to like parts wherever they occur, Figure 1 is a vertical sectional elevation of a structure embodying my invention. Fig. 2 is a front elevation of the modification of said structure seen in Fig. 3, and Fig. 3 is a vertical sectional elevation of said modified structure.

25 The footing comprises a thick slab or foundation of concrete having metal reinforcing bars or rods embedded horizontally therein. Some of these reinforcing bars or rods 2 are arranged longitudinally near the upper and 30 lower surfaces of the footing, and others, 3, are arranged transversely near the lower surface. Upon the footing, at or near the outer side thereof, is built a face-wall 4, of concrete, having reinforcing bars or rods embedded 35 therein near its outer surface. Some of the bars 5 in the face-wall are arranged horizontally, and others, 6, are arranged transversely, the transverse bars preferably being extended down into and embedded in the footing.

40 A series of vertical strengthening-ribs 7 are built upon the footing 1 transverse to the face-wall 4. These ribs 7 are of triangular shape, inclining upwardly from near the rear or inner side of the footing to the upper portion of the vertical wall. These ribs have 45 embedded therein reinforcing bars or rods whose ends are preferably anchored in the footing and in the walls resting on the ribs. This anchoring is conveniently effected by 50 doubling back the ends of the bars or rods to form hooks which engage the horizontal bars or rods in the footing and in the other walls, respectively.

In practice the several portions of my construction will be built simultaneously and in 55 one continuous mass of concrete by the use of

centering or false work, as is usual in concrete construction, and preferably the reinforcing metal will be corrugated bars of the kind fully shown and described in my application for Letters Patent therefor, Serial No. 194,362, filed by me February 19, 1904.

A structure of this general description is herein shown utilized in dam construction, though, obviously, it is also well adapted for 60 retaining-walls. In the construction shown the width of the footing is practically equal to or greater than the face-wall and is generally cemented water-tight to bed-rock.

In the construction shown in Fig. 3 the 70 face-wall 4 has a considerable inclination and rests upon the footing and upon the triangular ribs or transverse walls 7 on said footing. These transverse walls are preferably reinforced with horizontal bars 2^a, extending into 75 the face-wall, and with vertical bars 11, whose lower ends extend into the footing, and may have hooks for engaging the bars therein and whose upper ends extend into the face-wall. This construction is designed to have the 80 water bear against the outer surface of the inclined face-wall; but it is capable of use with the water entering between the ribs, in which case the reinforcing metal is embedded near the outer surface of the face-wall. In 85 either case the weight of the water contributes to the stability of the dam. In this construction it is unnecessary to fill in the space between the ribs, and consequently it is unnecessary to inclose said space with a wall at 90 the rear of the structure.

The construction shown in Fig. 1 is designed to have the vertical wall 4 used for the face-wall. This vertical wall has the horizontal bars 5 and vertical bars 6 embedded near 95 its rear and horizontal bars 5^a and vertical bars 6^a embedded near its front surface. The ribs 7 are built upon a footing, as described, and constitute buttresses for the face-wall. These ribs are of triangular 100 shape, and the space between them may be filled in with cheap material and inclosed with a rear wall 12, which rests against the inclined ends of the ribs. This rear wall 12 has horizontal bars 9 and upwardly-inclined 105 bars 10 embedded near its outer surface. The lower ends of these last-mentioned bars extend into the footing, and the upper ends extend to the front wall or to the uppermost portion of the construction, which is tied to 110 said front wall by horizontal bars 13.

In some cases where the construction is

liable to be exposed to water-pressure on each side it is desirable to have two vertical face-walls. In such cases the transverse ribs are of rectangular rather than triangular form.

Obviously my invention is applicable to other uses where it is desirable to increase the transverse strength of a wall, as in the case of bridge abutments, piers, and the like, 10 Consequently I do not wish to be limited to the exact details of constructions hereinbefore shown.

What I claim is—

1. A dam comprising a footing, a face-wall 15 thereon, and vertical ribs arranged transversely on said footing and having their ends inclined, and an inclined wall arising directly from said footing and resting against the inclined ends of said ribs, all made of concrete and reinforced with layers of longitudinally and transversely arranged metal rods, whereby the face-wall and the inclined wall are anchored to each other and to the footing.
- 25 2. A dam comprising a footing, a face-wall thereon, and vertical ribs arranged transversely on said footing and having their ends inclined, and an inclined wall arising directly from the footing resting against the inclined 30 ends of said ribs and uniting integrally the upper edge of the face-wall with the footing, all made of concrete reinforced with layers of longitudinally and transversely arranged rods of metal.
- 35 3. A dam comprising a footing, vertical ribs arranged transversely on said footing and having their ends inclined, and an inclined wall arising directly from said footing and resting upon the inclined ends of said ribs, 40 all made of concrete reinforced with metal rods, which anchor the inclined wall to the footing through said ribs.

4. A concrete dam comprising a footing, vertical ribs arranged transversely on said footing and having their ends inclined, and an inclined wall arising directly from said footing resting on the inclined ends of said ribs, said inclined wall having transverse bars whose lower ends are embedded in the footing, and said ribs having vertical rods 50 whose ends extend into the inclined wall and into the footing the width of said footing being substantially as great as the height of the inclined wall.

5. A concrete dam comprising a footing of 55 concrete reinforced with metal bars, vertical ribs of concrete arranged transversely on said footing, and an inclined wall resting on said footing and against said ribs, said inclined wall having transverse bars embedded 60 therein, and said ribs having horizontal bars extending into said wall and having vertical bars extending into said footing and into said wall, said vertical bars having hooks at their lower end arranged to engage the bars of 65 said footing.

6. A concrete dam comprising a footing of concrete reinforced with metal bars, vertical ribs of concrete arranged transversely on said footing, and an inclined wall resting on said 70 footing and against said ribs, said inclined wall having transverse bars embedded therein, and said ribs having horizontal bars extending from end to end thereof and into said wall and said ribs having vertical bars 75 extending into said footing and into said inclined wall thereby anchoring said walls together through said ribs.

St. Louis, Missouri, June 9, 1904.

ALBERT L. JOHNSON.
